UNITED STATES PATENT OFFICE

135,600

DESIGN FOR A PAIR OF OPHTHALMIC SPECTACLES

Harry Stolper, New York, N. Y.

Application August 25, 1942, Serial No. 108,028

Term of patent 7 years

To the Commissioner of Patents:

Be it known that I, Harry Stolper, a citizen of the United States, residing at New York, in the county of New York and State of New York, have invented a new, original, and ornamental Design for a Pair of Ophthalmic Spectacles, of which the following is a specification, reference being had to the accompanying drawing, forming part thereof.

Fig. 1 is a front elevational view of the front of a pair of ophthalmic spectacles, and

Fig. 2 is a plan view of the complete spectacles, showing my new design.

I claim:

The ornamental design for a pair of ophthalmic spectacles, as shown.

HARRY STOLPER.
